UNITED STATES PATENT OFFICE

HARRISON L. STALEY, OF MARTINSVILLE, INDIANA

BOILER TUBE CLEANER

Application filed March 5, 1928. Serial No. 259,037.

This invention relates to rotary cleaners which are employed for removing scale from boiler tubes and particularly to the type carried on the end of a flexible shaft or universal joint for cleaning bent or curved tubes, such cleaners comprising a rotary head carrying rotatable toothed cutters mounted on arms that extend beyond the body of the cleaner and which are thrown outwardly against the scale by centrifugal force.

Tube cleaners of this type have heretofore been arranged with independently swinging arms which permit the cleaner to be thrown out of balance when one of the arm members is forced inwardly by striking a projecting piece of scale, such movement producing a severe pounding of the head in the tube and causing thereby great damage to cutter parts. Further, cleaners of this type have been equipped with swinging arm members movably secured to the body by rivets, an arrangement which prohibits the making of quick repairs to the head, and furthermore, such cleaners have been provided with pivots or trunnions that carry all the rearward thrust of the arm which causes them to break as the head is forced through the tube.

It is the object of my invention, first, to provide a tube cleaner free of rivet connections so that repairs to it can be easily and quickly made, second, to provide a cleaner with facilities for eliminating all the rearward thrust of the arm members from the pivot pins or trunnions, third, to provide means for balancing the cleaner by operatively connecting the swinging arms in pairs, so that a movement of one arm produces a like movement of the connected arm, and fourth, to provide a cleaner in which the centrifugal pressure of one arm member is transferred by connecting means through the body and utilized by the opposite arm in the scale removing process.

With these and other desirable objects in view, reference is made to the accompanying drawings in which Figure 1 is a side elevation of the tool with rear pair of arms expanded; Figure 2 is a sectional view showing front pair of arms in closed position;

Figure 3 is an end view of the body with all parts removed; Figure 4 is a perspective view of one of the arms; Figure 5 is a side view of a cutter pin; Figure 6 is a side view of a pivot pin or trunnion; Figure 7 a perspective of a sliding thrust block; Figure 8 a modified form of means for connecting the arm to body; Figure 9 a modified form of a pivot pin or trunnion to be used in modification shown in Figure 8.

In the drawings, the numeral 2 represents the body of the cleaner which has a central screw connection 3 for rotating the head and preferably four radially disposed longitudinal slots 4 which are connected in pairs through the body by transverse slots 5, the same being at right angles to each other, one in the front portion of the body and the other in the rear.

Outwardly swinging arms 6 are pivoted in the longitudinal slots by pins 17, said arms having inwardly projecting lugs 7 with gear teeth thereon to connect operatively said arms in pairs through the transverse slots in the body. As one pair of arms is pivoted in the forward part of the body, I find it necessary to mount slidable thrust blocks 8 in the longitudinal slots on pins 9 to afford connecting means between the forward pair of arms and the threaded annular plate 10.

The arms are further provided with a longitudinal bore or aperture to receive a shaft or cutter pin 11; these shafts or pins have heads and project from the forward end of the arm to form journals for cutters 12 which are rotatably mounted between the head of the bolt and the front end of the arm. To secure these shafts to the arms a groove is cut in them transversely near the inward end to coincide with holes 18 in the swinging arm for receiving pin 13. These holes in the arms are so located that when the arms are at their farthest outward position the pins still remain within the confines of the longitudinal slots. It is desirable that the rear end 14 of the arm 6 be made circular to allow a sliding contact with the annular plate 10 and thrust block 8 in their swinging movement, and that the under side 15 of the arm be cut at an angle so as to engage the bottom of the lon-

itudinal slot to limit the outward movement of the swinging arm.

While a plural number of gear teeth may be cut on the inwardly projecting lugs 7, I prefer that only one tooth be cut on one arm and two part teeth on its mate so as to permit the paired arms to be parallel when in closed position. In all other respects the arms are identical in construction.

10 Facilities for removably pivoting the swinging arm 6 to the body are provided by a transverse key-hole slot in the arm formed by two intersecting hole-segments 16, 16a, the same being of different diameters. I have found that the easiest way of producing a hole of this shape is to first bore a hole of the larger diameter, plug it up with a metal of equal density and then bore the smaller intersecting hole, removing the plug thereafter. It is necessary that the part of the aperture designated by the number 16a be at least a half circle and connected to hole 16 by an opening equal to its diameter. Holes corresponding in size to the diameter of the part hole 16 are 15 provided in the side walls of the longitudinal slots 5. A pivot pin or trunion 17 is formed with heads 19 having the same diameter as the part hole 16 and with a central body 20 having a diameter equal to that of the part hole 16a, the said central body portion 20 having a length equal to the width of the arm.

To assemble head thrust blocks 8 are slidably mounted in the longitudinal slots 4 on the fixed pins 9 and the front pair of arms 35 placed in position with part hole 16 of the arm in alignment with the holes in the body member. The pivot pin 17 is then passed through the aligning holes and the arms forced forward which brings the surface of the arm 40 around the part hole 16a between the heads of the pivot pin. In like manner the rear pair of arms is secured in the body after which the annular threaded plate 10 is secured firmly against the end of the body and all the parts 45 are thereby locked in position. It will thus be seen by this assembly plan that the cleaner can be easily dismounted and parts replaced without loss of time.

In the arrangements of parts as herein described, it will be observed that the rearward thrust of the arms caused by the cleaner being forced against the scale in the tube is not carried by pins 17, but is carried by the annular plate 10 as the part hole 16 permits a 55 rearward movement of the arm.

A modified plan for locking the arms in the body member is shown in Figure 8. In this modification holes a' , a'' are bored in the side walls of the longitudinal slots 4 to form 60 a key-hole slot and a hole equal to the diameter of the part hole a'' is bored transversely through the swinging arm 6. A pivot pin b' having a central body section equal in diameter to part hole a'' and reduced end 65 sections equal in diameter to the part hole a'

is used and the assembly of which is the same as heretofore indicated for the preferred design.

Having fully described my invention, I claim as new:

1. In a tube cleaner, a head provided with a plurality of diametrically opposed longitudinal slots, transverse slots connecting said longitudinal slots, arms carrying rotatable cutters pivoted in said longitudinal slots and means in said transverse slots to connect operatively the arms in pairs.

2. In a tube cleaner provided with a plurality of diametrically opposed longitudinal slots, transverse slots through the body connecting said longitudinal slots, outwardly swinging arms carrying cutters engaging the longitudinal slots, inwardly projecting lugs on the arms engaging the transverse slots, intermeshing gear teeth on the projecting lugs to connect operatively the arms in pairs, said arms having key-hole slots therein, pivot pins passing through said slots and each having a reduced central section, and screw means to move the arms longitudinally to lockingly engage said reduced central sections of the pivot pins with the narrower portions of said slots.

3. In a tube cleaner comprising a rotary head having two pairs of diametrically opposed longitudinal slots therein, transverse slots through the body connecting the longitudinal slots in pairs, two pairs of outwardly swinging arms carrying rotatable toothed cutters mounted in the longitudinal slots, means in the transverse slots to connect operatively the swinging arms in pairs, pivot pins adapted to be positioned through the side walls of the longitudinal slots and means for locking the pivot pins in the body by a forward movement of the swinging arms.

4. The combination of a tube cleaner having a body, an outwardly swinging arm carrying a rotatable toothed cutter thereon and pivoted in said body, said arm having a key-hole slot therein the greater width of which is nearer the free end of the arm, a pivot pin having two end sections coinciding in diameter with said greater width, and a central reduced section coinciding with the smaller width of said slot, and means to move said arm forwardly to lockingly engage said smaller width with said central section of the pin.

HARRISON L. STALEY.
